CANOPY FLANGE

Stephen A. Young, Delphi, Ind.

Application March 15, 1951, Serial No. 14,499

Term of patent 14 years

(Cl. D91—3)

To all whom it may concern:

Be it known that I, Stephen A. Young, a citizen of the United States, residing at Delphi, in the county of Carroll and State of Indiana, have invented a new, original, and ornamental Design for Canopy Flange, of which the following is a specification, reference being had to the accompanying drawing, forming a part thereof, wherein:

Figure 1 is a top plan view of a canopy flange showing my new design.

Figure 2 is a side elevational view thereof.

Figure 3 is a side elevational view rotated about 30°.

I claim:

The ornamental design for a canopy flange, substantially as shown.

STEPHEN A. YOUNG.
